UNITED STATES PATENT OFFICE

FRANK C. HAMILTON, OF NEW YORK, N. Y., ASSIGNOR TO EUREKA PROJECTOR DEVICE CO., INC., OF NEW YORK, N. Y., A CORPORATION OF NEW YORK.

SHUTTER FOR USE WITH MOTION-PICTURE APPARATUS HAVING INTERLOCKING PARTS.

1,210,063.

Specification of Letters Patent. Patented Dec. 26, 1916.

Application filed September 30, 1915. Serial No. 53,233.

To all whom it may concern:

Be it known that I, FRANK C. HAMILTON, a citizen of the United States, residing at New York, in the county of New York and 5 State of New York, have invented certain new and useful Improvements in Shutters for Use with Motion-Picture Apparatus Having Interlocking Parts, of which the following is a specification.

10 This invention relates to the motion picture art, and concerns itself particularly with improvements in revolving shutters for use in projecting apparatus.

One of the objects of the invention is to 15 provide a shutter in which the usual opaque vanes are replaced by glass sectors, or vanes, which, while transparent, cause a destruction of focus or the diffusion of light rays passing through them, and to arrange for 20 ready and effective assembling of such vanes with the usual revolving shutter shaft of a projecting apparatus.

In the accompanying drawings, which are 25 to be taken as a part of this specification, and in which I have shown a merely preferred form of embodiment of the invention, Figure 1 is a side elevation of such an embodiment, with certain parts removed; Fig. 30 2 is a view similar to Fig. 1, of another embodiment; Fig. 3 is also a side elevation disclosing the embodiment of Fig. 1 or Fig. 2 with the addition of the parts omitted from 35 those figures; and Fig. 4 is a sectional view, on an enlarged scale, taken on the line 4—4 of Fig. 3.

Referring to the numerals on the drawings, 5 indicates a seat member, provided with a plurality of cut-through seats or slots, each of which is intended for dove-tail or interlocking engagement with the co-operant and correspondingly shaped shank of a vane 6. The seat member is transversely centrally bored at 7 to accommodate a sleeve 8, which is exteriorly threaded adjacent one end at 8^a, and provided with an aperture 8^b.

A duplicate pair of side shields 9, each of the outline indicated in Fig. 3, are centrally bored so as also to take about the sleeve 8 50 when said side shields are riveted or bolted to the seat member 5 and maintain said seat member and vanes 6 interlocked as aforesaid. It will be noted that none of these rivets or bolts pass through any of the vanes.

Each vane 6 is thicker in its shank than 55 elsewhere, and the arcuate edges of side shields 9 are inturned against arcuate shoulders, one carried on each side of each vane and marking the merging of a vane-blade into its shank. 60

A trifurcated flat spring 10 is riveted to one of said side shields as shown best in Fig. 3. This spring 10 has centrally offset therefrom a sleeve 10^a adapted to take about sleeve 8. Sleeve 10^a carries a threaded aperture 65 for a set screw 11; the set screw being spirally adjustable so that its shank may pass through sleeve 8's aperture 8^b and have the tip of the shank forced tight against the usual revolving shutter shaft 12. (Fig. 4) 70 usually found in projecting apparatus.

With sleeves 8 and 10^a thus mounted fixedly on shaft 12, the shutter is adjusted against end thrust on said shaft by means of a washer 13 and a nut 14 (Fig. 4). 75

A fillet, or hoop 15, may be employed as shown. Each of the vanes 6, instead of being opaque, as usual, is preferably of a transparent material which, when halted predeterminedly transversely of the light rays from the illuminator within the projecting apparatus, diffuses said light rays sufficiently to project onto the usual screen nothing more than apparently immobile and even area of illumination. Since, therefore, said 80 vanes 6 may most advantageously be constructed of glass, each preferably being a unitary molded piece, it is obvious that the interlocking arrangement between the seat member 5 and the shanks of the vanes, 85 renders possible the use of the side shields 9, to completely nest said vanes against any inadvertent withdrawal or loss from their preliminary interlocking with the seat member 5, but also permits said side shields 9 to 90 be fixed in place upon the seat member without any necessity for the vane shanks to be drilled or cut for the passage therethrough of bolts, rivets or other fasteners. 95

While the outlines of the vane shanks 100 shown in Fig. 1 differ from those shown in Fig. 2, and while the two uppermost ones in Fig. 2 differ in outline from the other one in said Fig. 2, it will be seen that the interlocking characteristic is present in each. In 105 passing, it may be stated that the types shown at 6^a in Fig. 2 are now deemed preferable.

For purposes which need not be mentioned in this application, one of each of the shown sets of vanes 6 is larger than the other vanes in the set. However, and despite the illustrative showing of Fig. 2, in any set all the vane shanks are preferably duplicates. This, together with the fact that easily demountable bolts passing through side shields 9 and seat member 5 may advantageously be employed as indicated, renders convenient and inexpensive, both from a manufacturing and from a maintenance standpoint, the substitution of a vane 6 in any of the cut through slots or seats of the seat member.

15 An important feature of the present invention is the provision of a single seat member 5 for the several vane shanks which, in addition to having the advantages aforesaid and obvious, may be constructed of some 20 cushioning material, such as hard rubber, compressed fiber, cork, leather or the like.

Inasmuch as many changes could be made in the above construction, and many apparently widely different embodiments of my 25 invention could be made without departing from the scope thereof, it is intended that all matter contained in the above description or shown in the accompanying drawings shall be interpreted as illustrative and not in a 30 limiting sense.

It is also to be understood that the language used in the following claims is intended to cover all the generic and specific features of the invention herein described 35 and all statements of the scope of the invention which, as a matter of language, might be said to fall therebetween.

I claim:

1. In a rotatable shutter having a plurality of removable vanes, a rotatable seat member from which said vanes project and provided with recesses removed from and opening away from the center of rotation of said member, each of said vanes having a 45 shank so conformed that with said shank sidewise advanced to become seated in one of said recesses said vane is locked in said recess against withdrawal radially of said center of rotation.

50 2. In a rotatable shutter having a plurality of removable vanes, a rotatable seat member from which said vanes project and provided with recesses removed from and opening away from the center of rotation of said member, each of said vanes having a shank so conformed that with said shank sidewise advanced to become seated in one of said recesses said vane is locked in said recess against withdrawal radially of said center of rotation, said recesses all being similar 55 and said shanks all being similar.

60 3. In a rotatable shutter having a plural-

ity of removable vanes, a rotatable seat member from which said vanes project and provided with recesses removed from and 65 opening away from the center of rotation of said member, each of said vanes having a shank so conformed that with said shank sidewise advanced to become seated in one of said recesses said vane is locked in 70 said recess against withdrawal radially of said center of rotation, in combination with a pair of duplicate side shields each overlapping said recesses.

4. In a rotatable shutter having a plurality of removable vanes, a rotatable seat member from which said vanes project and provided with recesses removed from and opening away from the center of rotation of said member, each of said vanes having a 80 shank so conformed that with said shank sidewise advanced to become seated in one of said recesses said vane is locked in said recess against withdrawal radially of said center of rotation, in combination with 85 a pair of duplicate side shields each overlapping said recesses, and fastening means for attaching said side shields one on each side of said seat member.

5. In a rotatable shutter having a plurality of removable vanes, a rotatable seat member from which said vanes project and provided with recesses removed from and opening away from the center of rotation 90 of said member, each of said vanes having a 95 shank so conformed that with said shank sidewise advanced to become seated in one of said recesses said vane is locked in said recess against withdrawal radially of said center of rotation, said seat member being 100 composed of some cushioning material.

6. In a rotatable shutter having a plurality of removable vanes, a rotatable seat member from which said vanes project and provided with recesses removed from and opening away from the center of rotation of said member, each of said vanes having a 105 shank so conformed that with said shank sidewise advanced to become seated in one of said recesses said vane is locked in said 110 recess against withdrawal radially of said center of rotation, in combination with a pair of duplicate side shields each overlapping said recesses, and fastening means for attaching said side shields one on each 115 side of said seat member, said seat member being composed of some cushioning material.

In testimony whereof I affix my signature in presence of two witnesses.

FRANK C. HAMILTON.
